His Attorney.

UNITED STATES PATENT OFFICE

THOMAS A. E. BELT, OF SCHENECTADY, NEW YORK, ASSIGNOR TO GENERAL ELECTRIC COMPANY, A CORPORATION OF NEW YORK

COMBINATION ELECTRICAL REGULATOR

Application filed April 29, 1930. Serial No. 448,401.

My invention relates to the regulation of electric circuits or electrical apparatus and particularly to the voltage regulation of alternating current feeder circuits.

It is well known that the sudden application of a comparatively large inductive load to an alternating current feeder circuit, such as the starting of oil burner, refrigerator or washing machine motors from house lighting circuits, causes a sudden dip in voltage on such circuits which in the cases mentioned manifests itself in an unpleasant momentary flicker in the lights or in a momentary disturbance in the reception from radio broadcast receiving sets which are energized from such circuits. Such dips in voltage are due to the fact that the comparatively large low power factor lagging starting current of load devices of the above mentioned type when drawn through the inductive reactance of the circuit produces a reactance voltage drop which is almost in phase opposition to the voltage impressed on the circuit. Thus the vector sum of these voltages is approximately equal to their arithmetical difference. In accordance with one feature of a preferred embodiment of my invention I provide means in the form of a series capacitor for producing a voltage rise in said circuit as a result of the flow of lagging current therethrough.

As the magnitude of the current taken by motor operated domestic load devices decreases as they get up to speed and as, at the same time, their power factor improves, the effect of the reactance drop in the line does not become as important, from the point of view of load voltage regulation, as does the resistance drop in the line. However, as it is important that incandescent lamps should operate at substantially constant voltage it is customary to provide means for regulating the voltage of said circuits. My invention, therefore, contemplates a simple and novel comparatively slow acting voltage regulator for regulating the voltage of alternating current circuits under steady conditions combined with instantaneously acting means for regulating the voltage of such circuits upon the sudden application of lower power factor inductive loads.

An object of my invention is to provide means for reducing the voltage dips in alternating current circuits when inductive loads are suddenly applied thereto.

Another object of my invention is to provide means for eliminating the flicker in lamps fed from alternating current feeder circuits to which motor operated loads are suddenly and intermittently applied. 55

A further object of my invention is to provide a novel voltage regulator for alternating current circuits which operates on the principle of flux control. 60

An additional object of my invention is to provide a voltage regulating system, for 65 alternating current circuits, including instantaneously operating means for minimizing voltage dips on feeder circuits when inductive loads are suddenly applied thereto combined with relatively slow acting means 70 for regulating the voltage of said circuits under all conditions of load thereon.

My invention will be better understood from the following description taken in connection with the accompanying drawings and 75 its scope will be pointed out in the appended claims.

In the drawings, Fig. 1 is a diagrammatic showing of a specific embodiment of my invention, while Fig. 2 is a vector diagram for 80 explaining the operation of one of the features of my invention.

Referring now to Fig. 1 wherein I have shown by way of illustration an embodiment 85 of my invention as applied to the regulation of the voltage of an alternating current feeder circuit which supplies energy to a typical domestic house load and in which 1 is an alternating current power supply circuit to which is connected an alternating current 90 secondary distribution or feeder circuit 2 through a distribution transformer 3. The load on circuit 2 is shown as comprising a plurality of unity power factor load devices, such as incandescent electric lamps 4 and a 95 plurality of intermittently applied low power factor loads, such as a motor operated electric refrigerator 5 and an oil burner 7. The latter is shown associated with a furnace 8 and is driven by a motor 9 under the control 100

of the usual room temperature thermostat 10. Such motor operated loads draw a relatively large lagging current at low power factor when starting. The series capacitor, 5 which may be connected in either circuit 1 or circuit 2, is shown as a variable condenser 11. This condenser may be connected directly in either of the circuits if desired, although considerations of physical size make 10 it desirable in most cases when connecting it in circuit 2 to connect it therein through a transformer, such as the series transformer 13 shown. A variable resistance 12 is preferably connected to series 15 with the capacitor 11 for preventing harmonic saturation of the series transformer under heavy surges of current. As one feature of my regulator depends for its operation upon the magnetic saturation or flux 20 control of a portion of a transformer core to secure the desired changes in voltage, means may be associated with the distribution transformer 3, for controlling the magnetic flux linking its windings, without departing from my invention in its broader aspects. However, as this would involve making changes in existing distribution transformers which have already been installed, 25 if my invention were to be applied to circuits 30 associated therewith, I have shown a separate transformer 14 in the form of a booster auto-transformer and it is the saturation or flux control of a portion of the core of this transformer which is varied for regulatory purposes. 35

In general terms, the variations in the voltage boost produced by transformer 14 are secured by varying the mutual flux threading 40 its primary and secondary windings, thus causing variations in its ratio of transformation. This result is secured by providing what may be referred to as a variable reluctance short circuit path for a portion of the primary winding flux. In the specific 45 embodiment of my invention illustrated this transformer comprises a four-legged core member having a primary winding 15, which is connected across circuit 2, wound on two of its legs 16 and 17, a secondary or voltage 50 boost producing winding 18, which is connected in circuit 2, wound on leg 16 and a regulating winding 19 wound on leg 17. Leg 17 forms a portion of the short circuit path for a part of the primary winding flux, the 55 rest of this path being the remaining right hand portion of the core. Regulating winding 19 may receive its energization from any suitable source of current and in the embodiment shown it is energized from circuit 2 60 through a rectifier 20. It is thus a saturating winding whose degree of energization controls the reluctance of leg 17. However, it will be obvious to those skilled in the art that the same result may be obtained by omitting 65 the rectifier so long as the magneto-motive

force of winding 19 bucks that of primary winding 15, for in such case variations in the energization of winding 19 will vary the effective reluctance of leg 17 because of its bucking action. Any type of rectifier may be employed but it is, of course, preferable to employ a full wave rectifier, and in the embodiment shown this rectifier is of the dry disk copper oxide type. The alternating current terminals of the rectifier may either be connected directly across the circuit 2 as shown or they may be connected to have a reduced voltage impressed across them, as by connecting them across a part of shunt winding 16. For varying the current through regulating winding 19, I employ a variable impedance device which may be of any type and which in the embodiment shown is a carbon pile rheostat 21. For controlling rheostat 21 I provide a variable force producing means which operates in accordance with variations in the voltage of circuit 2, such as a small induction disc type torque producing motor 22. This motor, which operates on a well known principle, has an operating magnet 23 connected to be responsive to the voltage of circuit 2. Magnet 23 has a core 26 provided with a split pole portion on one of the split parts of which is the usual short circuited shading coil 27. The torque of such a motor varies as the square of its impressed voltage and hence provides an unusually sensitive regulator operating means. An arm 24, which is fastened to the rotary element of motor 22, engages carbon pile 21 and thereby 95 provides the means by which the latter is controlled by the former. A suitable spring 25 serves to oppose the torque of motor 22 and thus to increase the pressure on the carbon pile 21 upon a decrease in voltage on circuit 2. 100

The operation of the illustrated embodiment of my invention is as follows. Assume that power supply circuit 1 is connected to a suitable source of alternating current (not shown) and that one or more lamps 4 are being energized from circuit 2 and that one or the other, or both, of the motor operated load devices 5 and 7 has just started to operate. The sudden rush of comparatively large lagging current required by the operating motors of these devices will ordinarily produce a considerable dip in the voltage of circuit 2 which would be attended by the well known flicker of the lamps connected to the circuit. This is illustrated in Fig. 2 where V_r represents the voltage at the terminals of the load devices, I the current taken by the load devices, IR the resistance drop in lines 2 and 1, IX the voltage drop through the inductive reactance of lines 1, 2 and transformers 3 115 and 14, and V_s the voltage of the source of energy connected to circuit 1. The difference between V_r and V_s indicates the magnitude of this dip in voltage. However, as I have provided a capacitance through which 120

the lagging current must pass a voltage drop is produced therein which, due to the fact that the current is lagging, is in reality a voltage boost. I have therefore been able to 5 eliminate or greatly minimize this voltage dip. Thus, referring again to Fig. 2, IX_c represents the voltage drop through the capacitance which is of course opposite in phase to the voltage drop through the inductive reactance of the lines. As shown, capacitance 10 11 is of such a value that this drop is equal in magnitude to the drop through the inductance of the circuit. However, by changing the magnitude of the capacitance it may be 15 made either greater or less than the drop through the inductance of the circuit. When the voltage drop IX_c is added to the other drops the vector V'_g represents a much smaller voltage of the source applied to circuit 1 20 for the same load voltage or, in other words, the addition of the capacitor greatly reduces the difference between the load voltage at light loads and at times when loads 5 and 6 25 have just been connected to the circuit for any given voltage applied to circuit 1.

However, as the power output of the motors operating the load devices increase as they come up to speed the power factor of the load improves so that the resistance drop 30 in the lines now becomes the predominating factor in reducing the load voltage and it is for regulating the load voltage under these conditions that the variable ratio transformer and its associated apparatus are employed. Thus, if the voltage of circuit 1 falls 35 the torque of motor 22 decreases, thereby allowing spring 25 to compress the carbon pile through the medium of arm 24, with the result that the resistance of the circuit including the saturating winding 19 decreases and the saturating current therethrough increases. The increase in saturation of leg 17 40 results in an increase in its effective reluctance, thus causing more of the primary winding flux to thread the secondary winding with the result that a higher voltage boost is induced in the secondary winding. In this manner the voltage drop in the circuit may be compensated for. Similarly, an increase 45 in voltage on circuit 2 increases the torque of motor 22, thereby decreasing the excitation of winding 19 with the result that more of the primary winding flux is diverted from the secondary winding and consequently the voltage 50 boost of this transformer is reduced. It should be noted that my regulator is not only operative to regulate the voltage of circuit 2 in accordance with changes in load thereon, but that it is also capable of regulating the 55 voltage of the circuit as a result of changes in the voltage impressed on it.

While I have shown and described a particular embodiment of my invention, it will be obvious to those skilled in the art that 60 changes and modifications may be made with-

out departing from my invention and I, therefore, aim in the appended claims to cover all such changes and modifications as fall within the true spirit and scope of my invention.

70

What I claim as new and desire to secure by Letters Patent of the United States is:

1. In combination, an alternating current circuit, transformer means for supplying a voltage boost to said circuit, a regulating winding for varying the ratio of the fluxes threading the primary winding and the secondary winding of said transformer, a variable current limiting means in series with said regulating winding, and means responsive to the voltage of said circuit for varying said current limiting means.

2. In combination, an alternating current circuit, a booster transformer including a voltage boosting series winding connected in said circuit and a shunt winding connected across said circuit, a saturating winding on said transformer, means connecting said winding across said circuit through a rectifier, a rheostat in series with said winding, and means including a torque producing motor for varying the resistance of said rheostat in accordance with variations in the voltage of said circuit.

3. In combination, an alternating current circuit, transformer means for producing a voltage boost in said circuit, and means, responsive to the voltage of said circuit, for varying the saturation of a portion of the magnetic circuit of the primary winding of said transformer means inversely with variations in the voltage of said circuit and independently of the condition of the magnetic circuit of the secondary winding of said transformer.

95

4. In a system of distribution, in combination, an alternating current power supply circuit, a distribution circuit, a distribution transformer connecting said circuits, a variable load connected to said distribution circuit, a booster transformer including a voltage boosting series winding connected in said distribution circuit and a shunt winding connected across said distribution circuit, a magnetic circuit common to both said windings, a separate magnetic circuit for diverting a portion of the flux of said primary winding from said secondary winding, a saturating winding associated with said second magnetic circuit, means connecting said saturating winding across said distribution circuit through a rectifier, a carbon pile rheostat connected in series with said saturating winding, an induction disc torque producing motor connected across said distribution circuit, and mechanical means connecting the rotor of said motor to said carbon pile rheostat.

105

5. In a voltage regulating system, a variable ratio transformer comprising a four legged core of magnetic material, a primary

110

115

120

125

130

winding linking two of the legs of said core, a secondary winding linking one of the legs linked by said primary winding and a regulating winding linking the other leg linked by said primary winding.

6. In combination, an alternating current circuit, one or more intermittently applied load devices connected to said circuit, said last mentioned load devices drawing an initial relatively large lagging current, a capacitor connected to said circuit so that the current flow therethrough is directly proportional to the current flow through said circuit, and means having a time delay for regulating the voltage of said circuit.

7. In combination, an alternating current circuit, one or more incandescent lamps connected thereto, one or more intermittently applied motor operated load devices connected thereto, a capacitor, means including a series transformer connecting said capacitor in said circuit, and voltage regulating means including a magnetically regulable variable ratio booster transformer and a voltage responsive element for regulating the voltage of said circuit.

8. In a system of distribution, in combination, an alternating current power supply circuit, an alternating current distribution circuit, a distribution transformer connecting said circuits, one or more incandescent lamps connected to said distribution circuit, one or more intermittently suddenly applied motor operated loads connected to said distribution circuit, a capacitor, means including a series transformer connecting said capacitor in said distribution circuit, a booster transformer connected to said circuit, a saturating winding for varying the reluctance of a portion of the magnetic circuit of the primary winding of said transformer, means for energizing said winding through a rectifier from said distribution circuit, a rheostat in the circuit of said saturating winding, and means for producing a force which varies in accordance with variations in the voltage of said distribution circuit for operating said rheostat.

In witness whereof, I hereunto set my hand this 22nd day of April, 1930.

THOMAS A. E. BELT.
